Primary Examiner — Ricky Pham(74) *Attorney, Agent, or Firm* — Pearl Cohen Zedek
Latzer Baratz LLP(57) **CLAIM**

The ornamental design for a knife, as shown and described.

DESCRIPTION

FIG. 1 is a top, front, right side perspective of the knife;

FIG. 2 is a right side elevation view thereof;

FIG. 3 is a left side elevation view thereof;

FIG. 4 is a rear elevation view thereof;

FIG. 5 is a front elevation view thereof;

FIG. 6 is a top plan view thereof; and,

FIG. 7 is a bottom plan view thereof.

The broken lines that appear on the drawings form no part of the claimed design and are included for illustrative purposes only.
